(57) **CLAIM**

The ornamental design for a charger capable of selectively receiving various standard plugs, as shown and described.

DESCRIPTION

FIG. 1 is a perspective view of a charger capable of selectively receiving various standard plugs showing my new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; and, FIG. 7 is a bottom plan view thereof.

The broken lines shown in the drawings are included for the purpose of illustrating unclaimed portions of the design and form no part of the claimed design.
